INVENTOR
W. Harry Titus
BY
John H. Marr
ATTORNEY

UNITED STATES PATENT OFFICE.

WEIMER HARRY TITUS, OF NEW YORK, N. Y.

EXERCISING DEVICE.

Application filed March 6, 1926. Serial No. 92,928.

The device, the subject of this invention is intended as an exercising device and while it may be better adapted for the development of the arms and legs, it may be used as a general exerciser and particularly a device intended for home use and where it is not practical or possible to secure an exercising device in a permanent position.

Another object of the invention is to provide a progressive exerciser, the resistance or strength of which may be increased as the physique of the user is improved, so that the exerciser may constantly offer a desirable resistance, which is essential for the complete development of one employing such a device.

The following is what I consider the best means of carrying out my invention and the accompanying drawing should be referred to for a complete understanding of the specification which follows.

In the drawing:

Fig. 1, is a side elevation of my device, the sections disclosing the construction of certain parts.

Fig. 2, is a plan view of one improved portion. Similar reference numerals indicate like parts in all the figures where they appear.

At 1 I show what I am pleased to term a floor board and which may be a member of wood or metal or other suitable material, oblong in shape and of desirable width and length.

Arranged upon the floor board are a plurality of wire members 2 and 3, each provided with a plurality of eyes or loops as shown at 4 and 5 and with extended ends as indicated at 6 and 7, which are adapted to be passed through suitable perforations in the board and to be clenched or bent over to secure the wire members firmly engaged with the board. The bent over portion of the wire members are indicated at 8 and 9.

The wire members 2 and 3 may be provided with any number of loops or eyes, for a purpose that shall appear later.

At 10 and 11 I show bales which may also be formed of wire and each bale is provided with a plurality of integrally formed loops or eyes as shown in 12 and 13. The free ends

of each bale are bent inward as shown at 14 and 15 and are received into a metallic tubular member 16.

Secured upon each metallic tubular member is a hand grip of wood as shown at 17 and 18.

Between the eyes 4 and 12 and 5 and 13 in the wire members 2 and 3 and bales 10 and 11, I arrange elastic and resilient members and in the drawing I show these members as springs, showing two springs to each bale, the springs being therefore, arranged in pairs.

The pair of springs connecting the bale 10 and wire member 4 are indicated at 19 and the pair connecting the bale 11 and wire member 5 are indicated at 20. These members should be of a sufficient length to allow the bales and handles to be carried a suitable distance from the board 1. The length of the springs may be varied as desired and as I have provided additional eyes 4, 5, 12 and 13, it will be noted that additional springs may be added as and when desired.

In using this device, the operator may stand, kneel, lie or sit upon the board 1 and operate the handles by moving them away from the board, either by means of the feet or the hands, the springs offering the desired resistance and retracting the handles when the arms or legs allow such retraction.

The advantages of this device reside in the fact that the handles may be moved at any angle from the board. Each handle may be operated individually and the range of operation is not limited, the dotted lines A and B suggesting positions that may be assumed by the handle 18.

It will be understood that modifications may be made within the scope of the appended claims, without departing from the principle or sacrificing the advantages of the invention.

Having carefully and fully described my invention, what I claim and desire to obtain is:—

1. An exerciser comprising a floor member, a plurality of wire members extending therethrough, the ends of said wire members being bent inwardly upon the underside of

said board, grip members and a plurality of spring members between each said wire member and its co-operating grip member.

2. An exercising device comprising a floor member, a plurality of wire members extending therethrough and having their ends turned inwardly and clenched to said floor member, each said wire member being provided with a plurality of eyes, grip members

each having a bale, the bale of each said grip member being provided with a plurality of eyes and spring members, each having one end secured to one of said eyes of a grip member and its opposite end secured to one of the eyes of one of the said wire members. 10 15

Signed at the city, county, and State of New York this 10 day of February, 1926.

W. HARRY TITUS.
